D12-203.

OR

D 13,418

EX

Design No. 13,418, dated November 14, 1882.

UNITED STATES PATENT OFFICE.

JOHN L. POPE, OF CLEVELAND, OHIO.

DESIGN FOR A CARRIAGE-STEP.

SPECIFICATION forming part of Design No. 13,418, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in ornamenting the upper surface thereof with star-like figures composed of ribbed or bar work, as will be hereinafter more particularly described.

In the accompanying photograph I have designated by the letter *a* only a few of the star-like figures. Each "star" is composed of six

radiating bars, *bbbbbb*. Around all the stars is a raised border, from which project inwardly short bars of raised work indicating parts of other stars, all of which latter is of course not essential to my novel design.

What I claim as of my invention, and desire to secure by Letters Patent, is—

A design for carriage-steps, consisting of the surface ornamentation of ribbed star-like figures, substantially as shown.

In witness whereof I have hereunto set my hand this 31st day of May, 1882.

JOHN L. POPE.

In presence of—

A. A. POPE,
C. M. COPP.
